UNITED STATES PATENT OFFICE.

ARTHUR R. DARLING, OF INDIANAPOLIS, INDIANA, ASSIGNOR TO EDWARDS INSTRUMENT COMPANY, OF INDIANAPOLIS, INDIANA, A CORPORATION OF INDIANA.

OZONATOR.

1,125,900.

Specification of Letters Patent. Patented Jan. 19, 1915.

Application filed April 9, 1913. Serial No. 759,913.

To all whom it may concern:

Be it known that I, ARTHUR R. DARLING, a citizen of the United States, residing at Indianapolis, in the county of Marion and State of Indiana, have invented a new and useful Ozonator, of which the following is a specification.

It is the object of my invention to provide an electrically operated ozonator which produces ozone with little or no contamination by oxids of nitrogen, requires but little electrical energy for its operation, requires but low tension conductors leading to the ozone-producing apparatus, is free from danger, is suitable for all the usual commercial lighting voltages and either alternating or direct current, and is simple and inexpensive in construction as well as in operation.

Ozone is produced when a sufficiently high electrical stress is set up in air, as for instance when corona or glow appears; and if violent sparking is avoided this ozone is practically free from oxids of nitrogen. According to my present invention, I produce ozone by such electrical stress in air. I set up this stress very economically and safely by Tesla currents; to this end I provide an induction coil having a primary winding and an open-circuited secondary winding the latter preferably having one end connected to the former and the two windings being located one inside and one outside of a tube of insulating material, and connect the primary winding in series with a condenser across the spark gap of a vibrator in series with an inductance across a supply line. The tube of insulating material is so mounted that there may be a circulation of air over at least one winding on it, and is preferably placed with its axis vertical so that this circulation will take place automatically through the tube upon the production of ozone. The conductors leading to the primary winding on the tube carry low tension currents.

The accompanying drawing illustrates a preferred form of my invention.

Figure 1 is a vertical longitudinal section, with some parts in partial elevation, through an ozonator embodying my invention, the electrical connections being shown somewhat diagrammatically; and Fig. 2 is a section on the line 2-2 of Fig. 1.

In the arrangement shown, a casing 10 is divided into three compartments, in the

center one of which is an inductance 11, a vibrator 12, and a condenser 13, and in the two outer ones of which are the ozone-producing devices. The inductance 11 serves as the actuating magnet for the vibrator 12, the adjusting screw 14 of the vibrator having its operating knob 15 above the top of the casing 10 and conveniently being mounted in a bridge 16 of conducting material crossing the top of the middle compartment. The condenser 13 is conveniently located beneath the inductance. On the bridge 16 are mounted two binding posts 17 and 18, which may be connected to the two sides of the supply circuit 19 respectively, the binding post 17 being in electrical connection with the bridge 16 and the binding post 18 being insulated from such bridge but connected by a wire 20 to one side of the inductance 11, the other side of said inductance 11 being connected by a wire 21 to the vibrator 12 and to one side of the condenser 13. The circuit is thus from one side of the supply line 19, through the binding post 17, the bridge 16, the adjusting screw 14, the vibrator 12, the wire 21, the inductance 11, the wire 20, and the binding post 18, to the other side of the supply line.

The ozone-producing device in its simple form comprises a tube 25 of insulating material, conveniently of glass, a primary winding 26, and a secondary winding 27, the primary and secondary windings being one on the inside and one on the outside of the tube. Conveniently, the primary winding is on the inside of the tube and the secondary winding on the outside thereof, as shown. The primary winding 26 conveniently consists of a few turns of corrugated metallic strip, the corrugations being most plainly shown in Fig. 2, and the secondary winding consists of a comparatively large number of turns of insulated wire wound on the outside of the tube 25 and shellacked to hold them in place. This ozone-producing device may be located wherever desired, but in the self-contained ozonator here illustrated there is one ozone-producing device in each end compartment of the casing 10. One end of the primary winding 26 of each ozone-producing device is connected by a wire 28 to the bridge 16, and the other end is connected by a wire 29 to the opposite side of the condenser 13 from that to which the wire 21 is connected. The circuit of the sec-

ondary winding 27 is left open, but one end of such winding, conveniently the lower end, may be connected by a wire 30 to the primary winding, also conveniently at the lower end.

If desired, there may be a second tube of insulation 35 surrounding and spaced from each tube 25, and an additional secondary winding 36 wound and conveniently sheltered in place on the outside thereof, one end of said winding 36 conveniently being connected to the opposite end of the secondary winding 27 from that to which the wire 30 is connected. Conveniently this connection is by a wire 36' connecting the upper ends of the two secondary windings. The lower end of the secondary winding 36 is left unconnected, or if there is no such secondary winding 36 the upper end of the secondary winding 27 is left unconnected. The top 40 and the bottom 41 of the casing 10 above and below the tubes 25 and 35 are perforated to allow the passage of air through such tubes.

In operation, the magnetic action of the inductance 11 causes the vibration of the vibrator 12 and the alternate making and breaking of the main circuit in the usual manner. For each break of the circuit, there is a rapid oscillating discharge from the condenser through the primary windings 26 in parallel and the spark gap between the vibrator 12 and its adjusting screw. By properly proportioning the inductance, the primary windings, and the condenser, the path of this discharge may be made resonant but exact resonance, though desirable, is not at all necessary. This rapid oscillating discharge through the primary windings sets up a high frequency, high potential electrification of the secondary windings. The electrical stresses between the primary windings 26 and the secondary windings 27, and between the secondary windings 27 and the secondary windings 36 produce discharges which ozonize and thus purify the air within and near the surfaces 25 and 35. This action is particularly noticeable, in the construction shown, adjacent those portions of winding 26 which are close to, but slightly separated from, the inner surface of tube 25, and with the axis of the tubes vertical there is a rapid circulation of air through the tubes.

I claim as my invention:

1. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and one end of said secondary winding being connected to said primary

winding, a winding on said tube being exposed to the atmosphere so that air can pass thereover and the axis of said tube being substantially vertical.

2. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and one end of said secondary winding being connected to said primary winding, and a winding on said tube being exposed to the atmosphere so that air can pass thereover.

3. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and one end of said secondary winding being connected to said primary winding, a winding on said tube being exposed to the atmosphere so that air can pass thereover and the axis of said tube being substantially vertical, a second tube, one of said tubes surrounding the other, and a second secondary winding on said second tube on the opposite face thereof from that toward the first tube, said second secondary winding being connected to the first secondary winding at the end of the latter opposite that which is connected to the primary winding.

4. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and one end of said secondary winding being connected to said primary winding, a winding on said tube being exposed to the atmosphere so that air can pass thereover, a second tube, one of said tubes surrounding the other, and a second secondary winding on said second tube on the opposite face thereof from that toward the first tube, said second secondary winding being connected to the first secondary winding at the end of the latter opposite that which is connected to the primary winding.

5. In combination, a tube of insulating material, a primary winding and a secondary winding wound one inside and one outside of said tube, an inductance and a vibrator connected in series for connection to a supply circuit, and a condenser, said pri-

- mary winding and said condenser being connected in series across the spark gap of said vibrator and one end of said secondary winding being connected to said primary winding, a winding on said tube being exposed to the atmosphere so that air can pass thereover and the axis of said tube being substantially vertical, a second tube, one of said tubes surrounding the other, and a second secondary winding on said second tube on the opposite face thereof from that toward the first tube, and said second secondary winding being connected to the first secondary winding.
6. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and one end of said secondary winding being connected to said primary winding, a winding on said tube being exposed to the atmosphere so that air can pass thereover, a second tube, one of said tubes surrounding the other, and a second secondary winding on said second tube on the opposite face thereof from that toward the first tube, and said second secondary winding being connected to the first secondary winding.
7. In combination, an inductance and a spark gap in series, a tube of insulating material, primary and secondary windings wound one on the inside and one on the outside of said tube, one end of said secondary winding being connected to said primary winding, and a condenser connected in series with said primary winding across said spark gap, said primary winding consisting of a corrugated strip.
8. In combination, an inductance and a spark gap in series, a tube of insulating material, primary and secondary windings wound one on the inside and one on the outside of said tube, said secondary winding being open circuited and sufficiently insulated to prevent disruptive discharges from it, and one end of said secondary winding being connected to said primary winding, and a condenser connected in series with said primary winding across said spark gap.
9. In combination, an inductance and a spark gap connected in series, a primary winding, a condenser connected in series with said primary winding across said spark gap, a secondary winding connected at one end to said primary winding and located near the latter, dielectric material separating the primary and secondary windings, and means for supporting said dielectric material so that air may pass over one of said windings.
10. In combination, an inductance and a spark gap connected in series, a primary winding, a condenser connected in series with said primary winding across said spark gap, a secondary winding connected at one end to said primary winding and located near the latter, dielectric material separating the primary and secondary windings, and means for supporting said dielectric material so that air may pass between one of said windings and the dielectric material.
11. In combination, a tube of insulating material, a primary winding and a secondary winding mounted one on the inside and one on the outside of said tube, a casing in which said tube is mounted with the axis of the tube substantially vertical, said casing being provided with openings communicating with said tube to allow the passage of air therethrough, an inductance, a vibrator connected in series with said inductance, and a condenser connected in series with said primary winding across the spark gap of said vibrator, the circuit of said secondary winding being open.
12. In combination, a tube of insulating material, a primary winding and a secondary winding mounted one on the inside and one on the outside of said tube, a casing in which said tube is mounted, said casing being provided with openings communicating with said tube to allow the passage of air therethrough, an inductance, a vibrator connected in series with said inductance, and a condenser connected in series with said primary winding across the spark gap of said vibrator, the circuit of said secondary winding being open.
13. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and the circuit of said secondary winding being open, and a winding on said tube being exposed to the atmosphere so that air can pass thereover.
14. In combination, a tube of insulating material, a primary winding and a secondary winding wound one inside and one outside of said tube, an inductance and a vibrator connected in series for connection to a supply circuit, and a condenser, said primary winding and said condenser being connected in series across the spark gap of said vibrator and one end of said secondary winding being connected to said primary winding, a winding on said tube being exposed to the atmosphere so that air can pass thereover, a second tube, one of said tubes surrounding the other, and a second secondary winding on said second tube on the opposite face thereof from that toward the first tube.

first tube, said two secondary windings being connected in series and their circuit being open.

15. In combination, an inductance and a spark gap in series, a tube of insulating material, primary and secondary windings wound one on the inside and one on the outside of said tube, the circuit of said secondary winding being open and said winding being sufficiently insulated to prevent disruptive discharges from it, and a condenser connected in series with said primary winding across said spark gap.

16. In combination, an inductance and a spark gap connected in series, a primary winding, a condenser connected in series with said primary winding across said spark gap, a secondary winding having its circuit open and located near the latter, dielectric material separating the primary and secondary windings, and means for support-

ing said dielectric material so that air may pass over one of said windings.

17. In combination, an inductance and a spark gap connected in series, a primary ²⁵ winding, a condenser connected in series with said primary winding across said spark gap, a secondary winding having its circuit open and located near the latter, dielectric material separating the primary and secondary windings, and means for supporting said dielectric material so that air may pass between one of said windings and the dielectric material.

In witness whereof, I have hereunto set ³⁵ my hand at Indianapolis, Indiana, this seventh day of April, A. D. one thousand nine hundred and thirteen.

ARTHUR R. DARLING.
